FOUNTAIN TOOTHBRUSH

Ludwig F. Perwas, Bronx, N. Y.

Application October 1, 1948, Serial No. 148,905

Term of patent 14 years

(Cl. D9—2)

To all whom it may concern:

Be it known that I, Ludwig F. Perwas, a citizen of the United States of America, residing at Bronx, county of Bronx, and State of New York, have invented a new, original, and ornamental Design for a Fountain Toothbrush, of which the following is a specification, reference being had to the accompanying drawing, forming a part thereof, wherein:

I claim:

The ornamental design for a fountain toothbrush, as shown.

LUDWIG F. PERWAS.
